[57] CLAIM

The ornamental design for a wafer for the welding and/or cutting of plastic tubes, as shown and described.

DESCRIPTION

FIG. 1 is a left side elevational view of a wafer for the welding and/or cutting of plastic tubes in accordance with this invention with the right side elevational view being a mirror image thereof;

FIG. 2 is a top plan view thereof;

FIG. 3 is a rear elevational view thereof;

FIG. 4 is a front elevational view thereof;

FIG. 5 is a bottom plan view thereof; and,

FIG. 6 is a perspective view thereof.

*Fig. 2.**Fig. 3.**Fig. 1.**Fig. 4.**Fig. 5.**Fig. 6.*
